Primary Examiner — Cynthia Ramirez*(74) Attorney, Agent, or Firm* — Banner & Witcoff, Ltd.(57) **CLAIM**

The ornamental design for a cart, as shown and described.

DESCRIPTION

FIG. 1 is a top, front, left perspective view of a cart showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom, front, left, perspective view thereof;

FIG. 8 is a top, front, right perspective view thereof; and,

FIG. 9 is a bottom, front, right perspective view of a cart thereof.

The broken lines showing the unshaded rectangular regions and the unshaded small circular elements represent features that form no part of the claimed design.

The broken lines in the figures represent portions of the cart which form no part of the claimed design.

1 Claim, 8 Drawing Sheets(56)
